UNITED STATES PATENT OFFICE.

ANDREW M. MCGILL, OF SAYRE, PENNSYLVANIA, ASSIGNOR, BY DIRECT AND MESNE ASSIGNMENTS, TO SAID MCGILL, AND ALEXANDER W. WHITEFORD AND GILBERT H. PEARSALL, BOTH OF NEW YORK, N. Y., AND FRANK N. HIBBITS, OF BETHLEHEM, PENNSYLVANIA, TRUSTEES.

LOCOMOTIVE-TENDER CISTERNS.

1,098,746.

Specification of Letters Patent. Patented June 2, 1914.

Application filed August 6, 1913. Serial No. 783,239.

To all whom it may concern:

Be it known that I, ANDREW M. MCGILL, of Sayre, in the county of Bradford, and in the State of Pennsylvania, have invented a certain new and useful Improvement in Locomotive-Tender Cisterns, and do hereby declare that the following is a full, clear, and exact description thereof.

The object of my invention has been to provide a locomotive tender cistern which shall have, among others, the following advantages: that it shall be possible to stop leaks without raising the cistern off the frame of the tender; that it shall be possible to stop most of its leaks without unloading the coal; and that it shall be capable of construction without the use of angle-irons at most of the joints between its plates. And to such ends my invention consists in the locomotive tender cistern hereinafter specified.

In the drawings Figure 1 is a plan view partially in section of a locomotive tender cistern embodying my invention; Fig. 2 is a vertical longitudinal sectional view of Fig. 1 on a line 2—2; Fig. 3 is a half end elevation; Fig. 4 is a half front elevation; Fig. 5 is a section of Fig. 1 on a line 5—5; Fig. 6 is a partial sectional view on the line 6—6 of Fig. 1; and Fig. 7 is a detail showing the connection of a brace with the bottom plates.

My invention is capable of embodiment in many different forms, and I have chosen the embodiment shown in the drawings as the best illustration of the principle of my invention known to me. Such embodiment, however, is to be regarded as typical only of many possible embodiments.

The general shape of my cistern is that common to locomotive cisterns. It consists, when looked at in plan view, of a substantially U-shaped cistern, consisting of a tank 1, having legs 2 which extend forward, as shown in Fig. 1, which inclose between them a coal space 3. The bottom 4 of the rear portion of the coal space is inclined, as shown in Fig. 2, so as to cause the coal to tend to flow to the front end of the tender, and the space 5 beneath said bottom is utilized for water. The coal also lies upon the tops of the legs 2, and for this purpose the

upper plates 6 of the said legs are inclined inward and downwardly, as shown in Fig. 4. The coal space is increased in height by 55 side walls 7 and a back wall 8 rising above the cistern proper, and by a front wall 9, which is open below so that access may be had to the coal. A manhole 10 is provided to permit a man entering the cistern proper 60 for the purpose of repairs and cleaning. So much of the construction shown in the drawings is old.

In practice, locomotive tender cisterns occasionally leak, and chiefly in the bottom 65 seams of the cistern. Prior to my invention, in order to repair such leaks it has been necessary to empty the tender of water and coal and to raise the cistern off the frame of the tender in order to get access 70 to the joints between the plates and the rivets holding the plates together. This operation not only causes expense to perform the operation itself, but it takes a considerable amount of time during which the 75 use not only of the tender but of the locomotive is lost.

By my invention it is unnecessary to lift the cistern off the tender frame in order to get at the joints and rivets even of the bottom plates, and for some repairs it is even unnecessary to unload the coal. To accomplish this object I construct the cistern in the following manner: The bottom, forward of the tank 1, consists of a plate or plates 11, 80 the width of the coal space and plates 12 the width of the legs 2. To these plates are to be secured the outside plates 13 and the inside plates 14 of the water legs. I turn upward the edges 11^a and 12^a of the plates 11 85 and 12 respectively, and fasten the said plates to each other and to the vertical plates 13 and 14 by rivets 15, which are thus made to stand horizontal. Both ends of the rivets are thus accessible for repairing, neither end 90 of the rivets being beneath the plates 11 or 12. Owing to this construction it is possible to tighten the rivets or replace them without lifting the cistern off the tender frame. Moreover, the joints between the plates are 100 exposed so that they can be calked from above. Further, the use of angle-irons, as heretofore, to connect the vertical plates with the bottom plates is also avoided, thus

saving expense, eliminating one joint for each angle-iron, and eliminating one row of rivets for each joint.

Braces 16 and 17 connect the inclined bottom 4 of the coal space with the bottom plates 11 and 12 of the cistern. At their lower ends, as shown in Fig. 7, they are riveted to the upturned edges or flanges of the plates 11 and 12, so that the rivets 15 are 10 also horizontal and can be readily gotten at within the cistern without requiring the cistern to be lifted off the frame of the tender.

As shown in Fig. 5, the joints between the inclined bottom plate 4 of the coal space and the adjacent top plate 6 of the water legs is formed by turning the edges or flanges 4^a and 6^a, respectively, of these plates downward, so that they can be united by horizontal rivets 15 and the outer edges of the plate 6 are also turned or flanged downward where they are united to the side plates 13. As the plates 4 and 6 are normally covered with coal, the construction just described enables leaks in the joints between these plates 20 to be stopped by working within the cistern, and thus the necessity for unloading the coal for leaks at this point is avoided.

It will be seen that every joint of my cistern can be repaired without raising the cistern off the tender frame, and that most of the joints which are liable to leak can be reached without unloading the coal.

I claim:

1. In a locomotive tender, the combination of a cistern and a frame upon which the cistern is mounted, said cistern comprising bot-

tom plates having upturned flanges formed thereon, said flanges being united by horizontal rivets.

2. In a locomotive tender, the combination of a cistern and a frame upon which the cistern is mounted, said cistern having bottom plates secured together, the joints of said bottom plates being united by horizontal rivets located above the bottom plates proper. 40

3. In a locomotive tender, the combination of a cistern and a frame upon which the cistern is mounted, said cistern comprising bottom plates having upturned flanges formed thereon, vertical plates, and horizontal rivets uniting said flanges and plates. 50

4. In a locomotive tender, the combination of a cistern and a frame upon which the cistern is mounted, said cistern having compartments both for coal and water, the partition between said compartments being composed of plates having flanges formed thereon, said flanges projecting toward the water, and rivets securing said flanges together. 55

5. In a locomotive tender, the combination of a cistern and a frame upon which the cistern is mounted, said cistern comprising bottom plates having upturned flanges formed thereon, and also comprising braces, and rivets securing said flanges and braces together. 60

In testimony that I claim the foregoing I have hereunto set my hand.

ANDREW M. MCGILL.
